G. H. PARSONS.
PNEUMATIC TIME SWITCH.
APPLICATION FILED JAN. 16, 1915.

Patented May 11, 1915.

UNITED STATES PATENT OFFICE.

GEORGE H. PARSONS, OF STAMFORD, CONNECTICUT, ASSIGNOR OF ONE-HALF TO
T. L. M. COUCH, OF STAMFORD, CONNECTICUT.

PNEUMATIC TIME-SWITCH.

1,139,066.

Specification of Letters Patent.

Patented May 11, 1915.

Application filed January 16, 1915. Serial No. 2,576.

To all whom it may concern:

Be it known that I, GEORGE H. PARSONS, a subject of the King of Great Britain, residing at Stamford, county of Fairfield,

5 State of Connecticut, have invented an Improvement in Pneumatic Time-Switches, of which the following is a specification.

This invention has for its object to provide an electric switch which may be easily operated to close the circuit and which shall be provided with a bellows, the action of which is to delay the opening of the circuit for a predetermined time after operation, my novel switch being applicable to various uses 10 in which it is desirable to have a manually operated switch remain in the circuit closing position for a short time after the operator has removed his finger from the circuit closing element.

20 As uses to which my novel switch is adapted, I will mention the lighting of an electric lamp in an unlighted hall or in a room where it is required to locate and light the gas or a lamp or to operate an electric 25 socket switch, or for use in connection with a cigar lighting fixture, or with an automobile horn to prolong the sound.

With these and other objects in view I have devised the novel pneumatic time 30 switch which I will now describe in connection with the accompanying drawing, in which I have illustrated the use of my novel switch in connection with an electric lamp, similar reference characters being used to 35 indicate like parts in all of the views.

Figure 1 is a perspective view illustrating the use of my novel switch in connection with an electric lamp, the apparatus being in place on a wall; Fig. 2 a perspective view 40 on an enlarged scale, the case being broken away to show the interior structure; Fig. 3 a detail elevation showing the position of the bellows and the spring contact in the open circuit position; Fig. 4 a vertical sectional view partly in elevation corresponding with Fig. 2, and Fig. 5 is a detail elevation partly broken away illustrating a variant arrangement of the valve.

I have shown the operative parts as 45 closed in a suitable case 10 adapted for attachment to a wall.

50 11 denotes an electric lamp the bulb of which lies outside the case, the base, indicated by 12, being attached to a suitable bracket or frame 13 within the case.

14 denotes a bellows which is secured to the case and the valve 15 of which may be arranged within the bellows as in Fig. 4 or on the outer side thereof as in Fig. 5.

16 denotes a spring the action of which 60 is to distend the bellows. In the form illustrated in Fig. 4, the upper end of the spring passes through a felt bushing in an eye 17 the shank of which passes through the hole 18 in the bellows and engages the 65 valve. The action of the spring therefore in this form is to simultaneously hold the valve closed and distend the bellows, air slowly forcing its way underneath the valve and into the bellows. In the form illustrated in Fig. 5, atmospheric pressure holds the valve closed, a small hole 19 being provided through which air may slowly enter the bellows when in the collapsed condition. The eye in this form engages a member of 70 75 the bellows.

20 denotes a battery from which an electric connection 21 leads to the lamp and a connection 22 leads to a contact spring 23 attached to the bracket.

80 24 denotes an electrical connection leading from the lamp and secured to the bracket in position to be engaged by contact spring 23.

25 denotes a stud or screw extending out- 85 ward from the bellows in position to engage contact spring 23 (see Fig. 3) when the bellows is distended and carry said spring out of engagement with electric connection 24, thus opening the circuit.

90 26 denotes a push pin normally retained in the retracted position by a spring 27. In Fig. 4 I have shown the inner end of this push pin as bearing against bellows spring 16, its action being to first raise the valve 95 by means of eye 17 and then to press the bellows to the collapsed condition. In the form illustrated in Fig. 5, the inner end of the push pin may act either against the bellows spring or against the bellows, in 100 pressing the bellows to the collapsed condition, the valve opening as soon as pressure is applied. As a means for adjustably limiting the collapsing movement of the bellows, I have shown a projection 28 105 on the bellows which is adapted to engage a stop nut 29 on an adjusting screw 30, the head 31 of which lies outside of the case and which is retained against longitudinal movement. Rotation of the screw will 110

move the stop nut toward or from the projection and thus determine to what extent the bellows shall be collapsed by operation of the push pin.

5 The operation is as follows:—The circuit is closed by the engagement of contact spring 23 with electrical connection 24. The normal position of the parts is with the bellows distended and the circuit broken 10 owing to the fact that contact spring 23 is held out of engagement with connection 24 by the stud extending from the bellows (see Fig. 3). Operation of the push pin causes the bellows valve to be raised and presses 15 the bellows to the collapsed condition. The movement of the stud backward from the position shown in Fig. 3 permits the spring contact to engage connection 24 and close the circuit. The push pin is returned to its 20 normal or retracted position by the spring the instant the pressure is removed. The circuit remains closed, however, and the lamp lighted until distention of the bellows causes stop 25 to force the contact spring 25 out of engagement with connection 24. The length of time required to distend the bellows and open the circuit is determined by adjustment of stop nut 29 which is engaged 30 by the projection on the bellows. If the bellows is allowed to only partially collapse, the time required for the distending movement is shortened. If the bellows is allowed to entirely collapse, the time required for distention is lengthened. As soon as the 35 pressure upon the push pin is relieved, the bellows spring will act to distend the bellows. The distending action is relatively slow as in the form illustrated in Fig. 4 the air must work its way under the valve slowly 40 as the spring holds it in the closing position and prevents it from being appreciably raised by atmospheric pressure. In the form illustrated in Fig. 5, atmospheric pres-

sure holds the valve closed and a small hole is provided in the bellows or the valve to 45 permit air to enter slowly.

Having thus described my invention I claim:—

1. A switch of the character described comprising an electric circuit, a bellows acting when distended to open the circuit, a spring controlled push pin adapted to collapse the bellows and close the circuit, a spring acting to distend the bellows and open the circuit, a projection on the bellows 55 and an adjustable stop adapted to be engaged by said projection to limit the collapsing movement of the bellows and consequently the time required for distention.

2. An apparatus of the character de- 60 scribed comprising an electric circuit, a bellows having a valve and acting when dis- tended to open the circuit, a spring acting to retain the bellows valve in the closing position and also to distend the bellows and 65 means acting to open said valve, collapse the bellows and close the circuit.

3. An apparatus of the character de- 70 scribed comprising an electric circuit, a bellows having a valve and acting when dis- tended to open the circuit, a spring acting to retain the bellows valve in the closing position and also to distend the bellows, a push pin acting to open said valve, collapse the bellows and close the circuit, and means 75 for regulating the collapsing movement of the bellows and consequently the time required for distention and the opening of the circuit.

In testimony whereof I affix my signature 80 in presence of two witnesses.

GEORGE H. PARSONS.
